UNITED STATES PATENT OFFICE

ERNST GEIGER, OF IREINGTON, NEW JERSEY

BUILDING CONSTRUCTION

Application filed May 1, 1928. Serial No. 274,183.

The present invention is concerned with improvements in building structures, being particularly designed to improve the construction of elevator garages of the general character disclosed in my Patent No. 1,636,560 issued on the 19th day of July 1927.

In its broader aspects, however, the invention is applicable to practically any building in which a bank of elevator shaftways are utilized or in which endless chains of connected movable storage compartments are moved in vertical shaftways and through horizontal crossways connecting the shaftways.

An object of the invention is to provide a building of this general character designed to promote the ready extinction of a fire occurring in an elevator car or occurring in any of the endless series of connected movable compartments.

With this in view, the lower end of each elevator shaftway, or in the case of an endless series of movable compartments, the lower cross space connecting each pair of vertical shaftways, may constitute a well completely surrounded by fire-proof walls. Preferably a fire inspection tunnel extends transversely through all of the wells and is disposed without the path of travel of the elevators in or through the wells. This tunnel permits the convenient inspection of any elevator or convenient observation of the conveyors of an endless chain as they pass through the lower cross space which connects their shaftways. It is also preferably equipped with means for discharging a heavy fire extinguishing gas through the tunnel walls into any well.

By virtue of this arrangement when an elevator fire occurs the well-like bottom of the elevator shaft is quickly filled with a heavy fire extinguishing gas and the elevator is dropped into the well where the fire is smothered by the gas.

In constructions such as that disclosed in my prior patent I may use remotely controlled valves for regulating the discharge of fire extinguishing fluid into the wells.

The arrangement is particularly adapted for installations where series of storage

cabins mounted on endless conveyors are utilized, since a fire occurring in any cabin may be put out by simply setting in motion the endless cabin supporting conveyor chains or the like so that the burning cabin is quickly passed through the gas filled well and the fire extinguished.

Other and more general objects of the invention are to provide a building structure in which the fire control features are embodied without material increase in the cost of the building and without causing any radical change in the general building design.

With the above noted and other objects in view the invention consists in certain novel features of construction and combinations and arrangements of parts which will be more fully hereinafter described and pointed out in the claims.

The invention may be more fully understood from the following description in connection with the accompanying drawings wherein:

Fig. 1 is a fragmentary transverse sectional view through the lower end of an elevator garage constructed in accordance with the invention, this view being taken approximately on the line 1—1 of Fig. 2.

Fig. 2 is another fragmentary sectional view through the lower end of the building taken approximately at right angles to Fig. 1 on the line 2—2 of Fig. 1, and

Fig. 3 is a wiring diagram showing the remote control mechanism for the fire extinguishing valves.

The drawings are for the most part diagrammatic and reference may be had to my prior patent for the structural details of the general type of garage building illustrated. The building designated at 10 is provided at opposite sides with banks of vertical shaftways 11 in which the duplex elevator cabins 12 run. An endless series of these cabins are mounted on an endless chain (not shown) which travels in suitable guideways 13. The cabins of the endless series pass from one shaftway 11 to the opposite shaftway 11 through crossways or spaces 14 arranged at the bottom of the building. The upper crossways are not shown here but may be seen in

my prior patent. The lower crossways are divided from each other by vertical partition walls 15. These walls also serve to separate the lower ends of adjacent shaftways 11 from each other. In other words the walls 15 extend the full width of the building and form wells through which the cabins pass as they travel around on the endless chain.

The section of the building disposed between the vertical shaftways 11 and between the upper and lower crossways 14 may be subdivided if desired into any suitable number of floors such as the floors 16, 17, 18. Preferably the entrance is through a driveway 19 at the street level. This driveway communicates with the car receiving floor 18 by a ramp 20 and with the car delivery floor 17 by a ramp 21. Additional ramps 22, 23 may lead from the floors 17, 18 to superjacent or subjacent floors 24, 25 if desired.

The fire inspection tunnel 26 of the present invention is preferably arranged at a level with the lower floor 25 and is accessible either by a ramp 22 or by a stairway 27 from the car receiving floor. This tunnel intersects the well-forming partition walls 15 and is provided with inspection windows 28 through which any well and the cabins passing therethrough may be readily observed. The floor 18 serves as the ceiling of the tunnel.

Inasmuch as a fire in one of the elevator cabins of the train would prove disastrous by spreading to the cabins above it unless rapidly checked I have devised means for readily converting any of the wells into a gas filled fire extinguishing chamber. Thus if a fire occurs in one of the cars, the train of cabins may be readily manipulated to bring the affected cabin into the gas filled well where the fire will be immediately extinguished.

For purposes of illustration I have shown a tank 29 of heavy fire extinguishing gas mounted in the tunnel 26, and leading from this tank a pipe 30 connected to valved discharging nozzles 31 which pass through the floor of the tunnel and discharge into the wells. The valves for these nozzles are preferably remotely controlled as for instance from a central control station 32 arranged on the main driveway 19. In Fig. 3 I have diagrammatically shown the control mechanism as consisting of a valve operating solenoid 33 in circuit with a suitable source of energy 34 closed by a switch 35 on a switch board 36, within the control station 32.

It may be noted that the control station 32 will also include means for remotely controlling the movement of the elevator cabins so that when a fire warning is received the burning cabin may be readily moved into its well and the well filled with fire extinguishing gas. Various gases might be used in this connection one example being carbon dioxide gas.

From the foregoing description it will be apparent that the fire inspection tunnel and

its associated mechanism is particularly adapted for use in connection with elevator garages of an endless chain type. In its broader aspects, however, the invention is applicable to any building in which a series of elevator shaftways are provided and means is desired for extinguishing fires in elevators. It will be obvious also that while I have referred to the present construction as a garage structure it might with slight modifications serve various other purposes where goods of any kind are stored in movable compartments or the like on endless flexible devices.

It will thus be seen that there is herein described a device in which the several features of this invention are embodied and which device in its action attains the various objects of the invention and is well suited to meet the requirements of practical use.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

I claim:

1. In a building structure including parallel vertical shaftways for an endless chain of storage elevators, and a crossway in the bottom of the building through which the elevators of the chain pass from one shaftway to the other, an inspection tunnel extending transversely of said crossway and disposed out of the path of travel of the elevators.

2. In a building structure a plurality of parallel vertical elevator shaftways, the lower ends of said shaftways being separated from each other by vertical partition walls and an inspection tunnel extending transversely of said shaftways, having windows therein affording a view of all of said shaftways.

3. In a building structure a plurality of parallel vertical elevator shaftways, the lower ends of said shaftways being separated from each other by vertical partition walls, an inspection tunnel extending transversely of said shaftways, having windows therein affording a view of all of said shaftways and valved fire extinguishing nozzles projecting through said tunnel into the walled lower ends of said shaftways adapted to discharge a heavy fire extinguishing gas into said shaftways.

4. In a building structure a plurality of parallel vertical elevator shaftways, the lower ends of said shaftways being separated from each other by vertical partition walls, an inspection tunnel extending transversely of said shaftways having windows therein affording a view of all of said shaftways and valved fire extinguishing nozzles projecting

through said tunnel into the walled lower ends of said shaftways, a supply of fire extinguisher disposed in said tunnel, and means for remotely controlling the valves.

5 5. In a building structure a pair of spaced parallel elevator shaftways and crossways at the top and bottom of the building through which elevators are adapted to be moved from one shaftway to the other, the lower of said 10 crossways and the lower ends of said shaftways being defined by vertical well-forming walls, and an inspection tunnel extending transversely through said well out of the path of travel of elevators therethrough.

15 6. In a building structure a pair of spaced parallel elevator shaftways, crossways at the top and bottom of the building through which elevators are adapted to be moved from one shaftway to the other, the lower of said crossways and the lower ends of said shaftways being defined by vertical well-forming walls, an inspection tunnel extending transversely through said wells and means for passing a fire extinguishing fluid through said tunnel 25 wall into said well.

7. In a building structure a plurality of pairs of spaced vertical shaftways, and crossways connecting said shaftways at the top and bottom, the lower crossways being separated by vertical partition walls from each other, and an inspection tunnel extending transversely through said walls and having windows therein permitting inspection of 30 said crossways.

35 8. In a building structure a plurality of pairs of spaced vertical shaftways, and crossways connecting said shaftways at the top and bottom, the lower crossways being separated by vertical partition walls from each other, a transverse inspection tunnel extending through said walls and having windows therein permitting inspection of any of said 40 crossways and means for passing a fire extinguishing gas through the tunnel into any 45 of said crossways.

9. In an elevator garage structure, or the like, a building providing at each side a parallel series of shaftways, crossways connecting opposite shaftways at the top and bottom, each pair of shaftways, and associated crossways accommodating an endless connected chain of storage elevators, the elevators of the chain being adapted to pass from one vertical shaftway to the other through said crossway, and an inspection tunnel extending transversely through all of said lower crossways out of the path of travel of the elevators having windows therein affording a view of all of said elevators as they pass through said crossways.

60 10. In an elevator garage structure or the like, a building providing at each side a parallel series of shaftways, crossways connected opposite shaftways at the top and bottom 65 each pair of shaftways and associated cross-

ways accommodating an endless connected chain of storage elevators the elevators of the chain being adapted to pass from one vertical shaftway to the other through said crossways, and an inspection tunnel extending 70 transversely through all of said lower crossways out of the path of travel of the elevators therethrough having windows therein affording a view of all of said elevators as they pass through said crossways, said lower crossways and the lower ends of the shaftways which communicate therewith being separated from laterally adjacent crossways and shaftways by vertical fire-proof partitions defining wells through which said tunnel 75 runs.

11. In an elevator garage structure or the like, a building providing at each side a parallel series of shaftways crossways connecting opposite shaftways at the top and bottom, each pair of shaftways and associated crossways accommodating an endless connected chain of storage elevators the elevators of the chain being adapted to pass from one vertical shaftway to the other 80 through said crossways, an inspection tunnel extending transversely through all of said lower crossways out of the path of travel of the elevators therethrough having windows therein affording a view of all of said elevators as they pass through said crossways, said lower crossways and the lower ends of the shaftways being separated from laterally adjacent crossways and shaftways by vertical fire-proof partitions defining wells 85 through which said tunnel extends, and means for optionally discharging a fire extinguishing gas into any of said wells.

12. In an elevator garage structure or the like, a building providing at each side a parallel series of shaftways crossways connecting the tops and bottoms of opposite shaftways, each pair of shaftways and associated crossways accommodating an endless connected chain of storage elevators, the elevators of the chain being adapted to pass from one vertical shaftway to the other through said crossways, an inspection tunnel extending transversely through all of said lower crossways out of the path of travel of the elevators having windows therein affording a view of said elevators as they pass through said crossways said lower crossways and the lower ends of the shaftways being separated from laterally adjacent crossways and shaftways by vertical fire-proof partitions defining wells through which said tunnel extends and means for optionally discharging a fire extinguishing gas into any of said wells said means comprising nozzles extending through 110 the walls of said tunnel into said wells.

13. In an elevator garage structure or the like, a building providing at each side a parallel series of shaftways crossways connecting the tops and bottoms of opposite shaft- 115 120 125 130

ways each pair of shaftways and associated crossways accommodating an endless connected chain of storage elevators, the elevators of the chain being adapted to pass from one vertical shaftway to the other through said crossways, an inspection tunnel extending transversely through all of said lower crossways said lower crossways and the lower ends of the shaftways which communicate therewith being separated from laterally adjacent crossways and shaftways by vertical fireproof partitions defining wells through which said tunnel extends, the space surrounded by the shaftways and crossways being horizontally subdivided near its lower end into floors and the ceiling of said inspection tunnel being formed by the lowermost of said floors.

14. In a building for storage purposes of the character in which endless series of storage conveyors travel orbitally around a central space and in which spaced vertical shaftways and upper and lower connecting crossways house the endless series of conveyors, a fire inspection tunnel extending transversely through the lower crossways.

15. In a building for storage purposes of the character in which endless series of storage conveyors travel orbitally around a central space, and in which spaced vertical shaftways and upper and lower connecting crossways house the endless series of conveyors, a fire inspection tunnel extending transversely through the lower crossways and said lower crossways being separated from each other by vertical fireproof partition walls.

16. In a building for storage purposes of the character in which endless series of storage conveyors travel orbitally around a central space, and in which spaced vertical shaftways and upper and lower connecting crossways house the endless series of conveyors, a fire inspection tunnel extending transversely through the lower crossways and said lower crossways being separated from each other by vertical fireproof partition walls, said tunnel housing a supply of fire extinguishing fluid and having valve controlled nozzles connected to said supply and projecting through the tunnel walls into the lower crossways.

17. In a building for storage purposes in which an endless series of storage conveyors travel orbitally on an endless flexible carrier, and in which parallel pairs of vertical shaftways house the conveyors and the conveyors at the ends of the shaftways are passed from one shaftway to the other, vertical walls defining wells enclosing the bottom of the shaftways of each pair and a fire inspection tunnel extending transversely through said wells.

18. In a building for storage purposes in which an endless series of storage conveyors travel in an orbital path and vertical shaftways connected by horizontal crossways house

the endless series of conveyors, a fire inspection tunnel extending transversely through one of said crossways.

Signed at New York, in the county of New York and State of New York this 28th day of April, A. D. 1928.

ERNST GEIGER.
